UNITED STATES PATENT OFFICE.

ELY KASRALOWICZ, OF NEW YORK, N. Y.

APPAREL APPARATUS.

967,131.

Specification of Letters Patent. Patented Aug. 9, 1910.

Application filed November 18, 1909. Serial No. 528,682.

To all whom it may concern:

Be it known that I, ELY KASRALOWICZ, a citizen of the United States, residing at New York, in the county of New York and State 5 of New York, have invented certain new and useful Improvements in Apparel Apparatus; and I do hereby declare the following to be a full, clear, and exact description of the invention, such as will enable others 10 skilled in the art to which it appertains to make and use the same.

My invention relates to wearing apparel, but has particular reference to apparel-apparatus for manufacturing clothing, being 15 especially suited for the manufacture of ladies' suits, coats, or waists, and having for its object the production of a garment-form which accurately corresponds in shape with the human form to be fitted, and possesses 20 the added advantages of lightness, cheapness, strength and durability.

The invention will be hereinafter described and particularly pointed out in the claims following.

25 In the accompanying drawings which form part of this application, and whereon corresponding characters refer to like parts in the several figures: Figure 1 represents in perspective the flexible fabric outline, or 30 outer lining, of a garment-form inside out, same being hereinafter designated a "try on." Fig. 2 is a vertical central section through Fig. 1 showing the "try on" in final shape, and mounted upon suitable end 35 blocks. Fig. 3 is a view corresponding with Fig. 2 except that the inner coating has been thickened and the end blocks removed. Fig. 4 is a perspective view of the completed garment-form, broken away at its lower portion for the purpose of displaying a filling 40 of cork or analogous material, and, Fig. 5 is a fragmentary view in horizontal section taken through the back center of the form at a point between the neck and waist line.

45 Reference being had to the drawings and numerals thereon, 1 indicates an envelop or casing of textile or other flexible material as an outer cover for the garment-form in the course of manufacture, same being first 50 accurately fitted upon the human form or

figure for which intended, and then turned inside out thus placing the seams 2 of the so-called "try on" upon the inside. Within the neck of try-on 1 is a circular neck block 3 having a peripheral groove 4, a central upstanding detachable handle 5, and a central depending rod 6 the latter rigidly affixed to said block and constituting part of an adjustable supporting standard. To this block 3 the neck of try-on 1 is temporarily 55 but securely attached by means of a flexible band or cord 7 drawing it into the peripheral groove 4, while similarly the lower edge of said try-on is secured by agency of a cord or band 8 in one of the peripheral 60 grooves 9, 10 or 11 in the edge of a base block 12 as shown by Fig. 2. The said block 12 is by preference elliptical in form, and, rising from the center thereof is a tubular member 13 constituting part of the extensible supporting standard 6—13 in telescopic 65 relation, the former adapted to slide vertically within the latter, and to be secured in predetermined relative position by agency of a set screw 14. The said base block 12 is 70 pierced transversely at one side of its vertical center by an opening 15, serving also as a charging passage, interiorly threaded as at 16 to receive a plug 17 in screw threaded 75 relation, said plug in turn being perforated 80 as at 18 to receive a suitable coupling 19 for an air pump (not shown), while from the central underside of this block 12 projects a detachable handle 20 corresponding with 85 the upper handle 5 aforesaid.

Stitched within the back of the try-on 1 at its center, and extending from the neck to a point approximating the waist line, is a vertical narrow stiffening rib 21, flat in cross section as indicated by Fig. 5, and steam 90 bent or otherwise shaped in substantial conformity with the figure to be fitted, while to complete the garment-form try-on 1 is blown up by air pressure as indicated by Fig. 2, lined by an interior coating of plaster of paris, cement, or other hardening composition 22 in which seams 2 and the rib 21 become embedded, is thereupon removed from the blocks 3 and 12, reinforced by more 95 of the hardening composition 22, filled with 100

a packing of cork or other light material such as 23, and finally closed at top and bottom by disks of canvas or other fabric 24 as clearly shown by the complete Fig. 4.

5 This being a description of my invention including the apparatus by agency whereof the completed article of manufacture is produced, I will now proceed to describe briefly its operation. Presuming that a try-on, 10 such as illustrated by Fig. 1, is first shaped upon the subject or human form for which the garment-form is intended to serve as a dummy, this "try-on" is then turned inside out placing seams 2 upon its interior, stiffening rib 21 of proper curvature is stitched in place, and into said "try-on," by agency of cord 7, the neck block 3 is secured. Likewise by agency of cord 8 the opposite or lower edge of "try-on" 1 is secured in one 15 or the other of the grooves 9, 10 or 11 according to the approximate hip measurement of the subject to be fitted. The height of the subject being known, the telescoping standard 6, 13 is adjusted accordingly, and 20 secured through opening 15, by means of the flat head set screw 14. A thin solution of plaster, cement, rubber, or other compound capable of rapidly hardening is next introduced into the interior of "try-on" 1 25 through arm or charging passage 15, the whole being rapidly turned in a horizontal position upon the handles 5, 20, so as to coat the interior to render it practically airtight. The charging passage 15 is next 30 closed by the introduction of plug 17, through which, and its coupling 19, an inflating medium such as air pressure from an air pump or other suitable source of supply is introduced to fill out and impart to the 35 garment-form its shape as shown by Fig. 2. Block 12 thereupon being removed the interior wall 22 of plaster or other suitable material may now be thickened as shown in Fig. 3, by merely introducing additional 40 material, or, if preferred this may, of course, be accomplished previous to the removal of said block 12, the additional material in that event being introduced through said 45 charging passage 15. But in any case after completion of the outer hardened shell or 50 casing the same is by preference filled with pulverized cork or any other analogous material such as 23, the structure then being completed by top and bottom closures sewed 55 or otherwise attached to the top and bottom edges of the garment-form as shown by Fig. 4 representing the completed article.

With this or substantially this system and 60 apparatus, it is quite obvious that an exact model of the human form to be fitted may be produced with accuracy and precision, and that a garment or garments of wearing apparel may be fitted thereto with the same degree of accuracy, but without the necessity 65 of tedious fittings and trials upon the per-

son of the customer. And, moreover, the more important measurements such as height and hip circumference being furnished, it is only necessary to have in addition the envelop or "try-on" 1 to insure accurate results even though the tailoring is to be done at a point or city very remote from the location of the subject or customer. 70

Having thus described my invention, what I claim and desire to secure by Letters Pat- 75 ent is:

1. An apparatus for the manufacture of garment forms comprising in combination, air-tight closures for opposite ends of an inflatable envelop, an extensible connection 80 between said closures, means carried by said extensible connection for locking same in predetermined position, and means for introducing an inflating medium.

2. An apparatus for the manufacture of 85 garment forms comprising in combination, air-tight closures for opposite ends of an inflatable envelop, a supporting rod extensible longitudinally within said envelop, and means for introducing an inflating medium. 90

3. An apparatus for the manufacture of garment forms comprising in combination, neck and base blocks detachably secured to opposite ends of an inflatable envelop, an adjustable connection between said blocks, 95 and means for introducing an inflating medium through said base block.

4. An apparatus for the manufacture of garment forms comprising in combination, neck and base blocks detachably secured to 100 opposite ends of an inflatable envelop, handles outwardly projecting from each of said blocks, an adjustable connection between said blocks, and means for introducing an inflating medium through said base block, 105 substantially as described.

5. An apparatus for the manufacture of garment forms comprising in combination, neck and base blocks detachably secured to 110 opposite ends of an inflatable envelop the latter of said blocks being provided with an opening, a plug or closure for said opening, and means for introducing an inflating medium through one of said blocks.

6. An apparatus for the manufacture of 115 garment forms comprising in combination, neck and base blocks detachably secured to opposite ends of an inflatable envelop the latter of said blocks being provided with an opening, a screw plug or closure for said 120 opening, and a tubular air-pump-coupling through said plug.

7. An apparatus for the manufacture of garment forms comprising in combination, air-tight closures for opposite ends of an 125 inflatable envelop, a sectional connection between said closures longitudinally adjustable, and means for locking said connection in adjusted position.

8. An apparatus for the manufacture of 130

garment forms comprising in combination, air-tight closures for opposite ends of an inflatable envelop, an adjustable connection between said closures telescopically arranged, and means carried by said adjustable connection for locking the same in adjusted positions.

In testimony whereof I affix my signature, in presence of two subscribing witnesses.

ELY KASRALOWICZ.
